UNITED STATES PATENT OFFICE.

HARRY H. BRANN AND GEORGE H. TENBROOK, OF SAN FRANCISCO, CALIFORNIA,
ASSIGNORS TO HAVISIDE COMPANY, OF SAN FRANCISCO, CALIFORNIA, A COR-
PORATION OF CALIFORNIA.

LADDER.

Application filed November 23, 1921. Serial No. 517,164.

To all whom it may concern:

Be it known that we, HARRY H. BRANN and GEORGE H. TENBROOK, citizens of the United States, residing at the city and county of San Francisco and State of California, have invented new and useful Improvements in Ladders, of which the following is a specification.

This invention relates to ship ladders and especially to that type which is known as "Jacob's ladders."

Ship ladders of the type referred to are usually sectional in construction and flexible to permit the ladders to be rolled or folded into as small a unit as possible for storage on board ship, etc., when not in use. Each section of a ladder of this character carries one rung or step and the several sections are usually connected by a pair of parallel ropes or cables disposed on each side, which are pulled together and lashed or seized between each ladder section. Two lashed or seized connections are thus formed between each step or section of the ladder and are from certain points of view objectionable; first because the connections are stiffened to such an extent as to render folding of the latter difficult, and secondly because the lashing or seizing is subjected to considerable strain when folded or bent and therefore often gives away.

One of the objects of the present invention is to overcome the objections referred to and to generally improve and simplify the construction of ladders such as described.

Another object, and one more specifically stated, is to connect the several sections of a ladder by a pair of cables one on each side and to so reeve each cable that seizing between the sections will be avoided and greater flexibility obtained.

Further objects will hereinafter appear.

The invention consists of the parts and the construction, combination and arrangement of parts as hereinafter more fully described and claimed, having reference to the accompanying drawings, in which—

Fig. 1 is a front view of the ladder.

Fig. 2 is a side elevation of the same, said elevation being partially in section.

Referring to the drawings in detail, A indicates in general a ladder constructed of a series of side sections 2—2, 3—3 and 4—4, which are interspaced and connected

by means of rungs or steplike members 5. 55 The particular outline or shape of the side sections is more or less immaterial, but they are preferably elliptical in shape as shown in side elevation. The opposite edges are grooved from end to end as illustrated at 60 6 and a cable 7 is reeved about the side sections to flexibly connect the same as will hereinafter be described. In the present instance two cables are employed, one for each series of side sections and as both cables are 65 reeved in the same manner, the description of one will suffice.

The cables employed for this purpose are generally spoken of as lanyards. A free end is provided as indicated at 8 which serves 70 the function of fastening the ladder when swung overboard to the rail, eyebolts or whatever may be most handy or convenient. The free ends may therefore be of any suitable length as they only serve the function 75 of a fastening or securing means. The cable is wound one turn about a thimble such as illustrated at 9, and it is then reeved alternately around opposite sides of the side sections 2, 3 and 4, as shown. It is then 80 passed around the lowermost section 4 as indicated at 10, and again alternately reeved around opposite sides as just described, the free end finally passing around the thimble 9, and being secured to the long end 8 by 85 means of lashing or seizing as shown at 11. By reeving the cable in this manner, it can be seen that a crossing will be formed between each ladder section as indicated at 12 and 13, and that this section will be sufficiently flexible to permit the ladder sections to be folded or rolled with relation to each other when the ladder is to be stored away.

As previously stated there are two cables employed as shown in Fig. 1, and it should 90 be understood that both cables are reeved about the side sections in a similar manner. The cables serve two functions, first that of flexibly connecting the side sections, and secondly that of maintaining an alignment between the same. Such alignment is secured by passing the cable through itself at the intersecting points indicated at 12, 13 and 14, that is during the reeving of the cable a marline-spike or the like is employed. For instance when the cable has been passed around the lowermost section 4, as indicated at 10, it is then brought

up around the opposite side shown at 10^a, and it can be seen that it will cross itself at the point 13 so that it may be reeved around the side 15 of the next side section. At this point the first section of the cable is separated by inserting a marline-spike or like tool and the cable end is passed through itself as shown at 16. This is of importance as it eliminates the use of lashing or seizing of any nature and it furthermore permits absolute alignment of the side sections. For instance if the cables should be placed side by side at the intersecting or crossing points shown at 12, 13 and 14, it is obvious that perfect alignment could not be obtained, and furthermore that displacement of the cable with relation to the grooves 6 might take place. Such displacement however is avoided by passing the cable through itself at each intersecting point. The usual lashing is eliminated and the connection is rendered more flexible.

From the foregoing it can be seen that an exceedingly simple and substantial ladder has been provided; perfect alignment between the successive side sections is secured; seizing between the connections is eliminated, and greater flexibility is attained, thus permitting the sections to be folded closely against each other when the ladder is not in use, and furthermore relieving the cable of all strains, as the fold, whether made in one direction or another, will follow the natural bend of the cable. In the present instance a comparatively short ladder, consisting of only three sections has been shown, but it is obvious that the number of sections employed may be increased or decreased proportionately to the length required; similarly while the structure as a whole is more or less specifically illustrated, we wish it understood that various changes in form and proportion may be resorted to within the scope of the appended claims. We also wish it understood that the materials and finish of the several parts employed may be such as the experience and judgment of the manufacturer may dictate or varying uses may demand.

Having thus described our invention, what

we claim and desire to secure by Letters Patent is—

1. A ladder of the character described, comprising spaced sides, each side comprising spaced sections and a pair of cables, each section having a surrounding groove, and rungs connecting the sections of opposite sides, said cables being alternately reeved around opposite sides of said sections in the respective grooves and thereby embracing the sections, each cable crossing its companion cable between said sections and at such points of crossing being reeved one through the other in alignment with the grooves of the sections so as to insure against displacement of the cables from the grooves.

2. A ladder of the character described, comprising spaced sides, each side comprising spaced sections and a pair of cables, rungs connecting opposite sections of opposite sides, the cables being alternately reeved around the edges of said sections with each cable of each side crossing and being reeved one through the other in alignment with the sections so as to maintain the sections in alignment when the ladder is extended.

3. A ladder of the character described comprising spaced sides, each side composed of spaced sections, a thimble and a pair of cables, each section and each thimble having a groove in its edge and the cables being alternately reeved around opposite sides of said sections in the respective grooves and embracing the sections and also extending in opposite directions into the grooves of the respective thimbles, each cable crossing its companion cable between said sections and between the uppermost section and the corresponding thimble and at such points of crossing being reeved one through the other in alignment with the respective grooves of the sections and corresponding thimble so as to provide for flexibility and maintain the sections of each side in alignment with the respective thimble, and rungs connecting opposite sections of the opposite sides.

HARRY H. BRANN.
GEORGE H. TENBROOK.
